Int. Cl. D6—01

U.S. Cl. D5—4

This is a continuation-in-part application of my previously copending application, Serial No. D. 8,979, filed Oct. 12, 1967, and entitled Teddy Bear Bed, which application is now abandoned.

I claim:

The ornamental design for a bedstead or the like, substantially as shown and described.
